UNITED STATES PATENT OFFICE.

CHARLES O. COZZENS, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

Original application filed November 24, 1917, Serial No. 203,770. Divided and this application filed September 17, 1920. Serial No. 410,921.

To all whom it may concern:

Be it known that I, CHARLES O. COZZENS, a citizen of the United States, residing at Southbridge, in the county of Worcester and 5 State of Massachusetts, have invented certain new and useful Improvements in Ophthalmic Mountings, of which the following is a specification.

This invention relates to improvements in 10 ophthalmic mountings and has particular reference to that type of mounting shown in my application filed November 24, 1917, Serial Number 203,770, of which the present case is a division, that being a type in which 15 spring actuated guards are employed for retaining the mounting in position on the face of the wearer, being commonly designated by the term fingerpiece mounting.

One of the principal objects of the present 20 invention is the provision of novel and improved construction of pivot support or bearing for a mounting of this character and of improved means for uniting the pivot connections with the frame portions of the 25 mounting.

A further object of the present invention 30 is the provision of a novel and improved type of construction in which the pivot structure and associated parts are enclosed or protected in place of being exposed to dirt, action of perspiration and the like, and in which the parts shall be concealed and protected, and a more neat appearance of the 35 mounting provided.

35 A further object of the invention is the provision of a novel and improved construction of mounting particularly adapted for use in connection with what is commonly termed a combination frame, that is to say, 40 a frame in which metallic and non-metallic parts are combined in a single mounting.

Other objects and advantages of my present construction should be readily apparent by reference to the following specification 45 taken in connection with the accompanying drawings, and it will be understood that I may make any modifications in the specific details of construction shown and described within the scope of the appended 50 claims without departing from or exceeding the spirit of my invention.

Figure I represents a front view of a mounting constructed in accordance with

and embodying the principles of my invention.

Figure II represents a vertical sectional view of one form thereof.

Figure III represents a similar sectional view of another form thereof.

Figure IV represents a plan view of the 60 construction as illustrated in Figure III.

In the drawings, in which similar characters of reference are employed to denote corresponding parts throughout the several views, the numeral 1 designates the bridge 65 or center connecting the two frame portions, each of said frame portions comprising an inner metallic portion 2 and an outer non-metallic portion 4, the outer non-metallic frame being suitably united to the bridge 70 1 and to the pivot block or plate 16 as by the fastening members 3.

In that form of my invention illustrated in Figure II of the drawings, I have shown the metallic frame 2 as split and secured at 75 one end to the bridge 1 and at the opposite end as carrying the block or sleeve 16. This member 16 has a central large recess 17 of sufficient size to receive the guard or finger-piece lever 11 with its tubular upstanding portion 10 and encircling actuating spring 12, the sleeve having arcuate slots formed at the bottom through which the lever may be operated, the parts being otherwise entirely enclosed by the member 16. In this 80 form I have shown the pivot post 18 as formed integral with and extending upwardly from the bridge 1, while the securing screw 14 overlies the upper portion of the post 18, the tube 10, spring 12 and member 16 bearing against the top of the member 16 85 to tightly clamp it against the bridge, thus uniting the ends of the frame and concealing the remaining parts, the screw extending downwardly through the post 18 and as shown into the bridge to securely lock the 90 parts together.

In Figure III, I have shown a slightly 95 different form of the invention in that in this form the pivot is separate from in place of integral with the bridge and has a reversely extending or overhanging portion receiving the spring. In this form the pivot comprises the cylinder 21 having a lower threaded end 22 engaged in the bridge and a reversely extending spaced flange 23 pro-

viding a recess to receive the spring 12, and having a socket as at 24 to receive the projecting end of the spring, the portion 21 being provided with a shoulder 25 adapted to 5 rest on the upper face of the lever 11, while the overhanging portion 23 rests against the outer edge of the lever and thus forms an additional steadyng member for the lever exterior to the spring 12 which is thus practically entirely encased. In addition the portion 16' forms a sleeve or housing enclosing the post 21 and associated parts and extends downward into tight engagement with the bridge except for the arcuate slots 15 through which the lever operates being secured in position as by the screw 14' engaging the upper portion of the post. In this form of the invention by loosening of the screw 14' the casing 16' may be raised to 20 open the frame for insertion or removal of a lens without in anywise disturbing the lever, pivot and actuating spring, these parts being concealed and protected even when the frame has been opened for inter- 25 changement of a lens.

From the foregoing description taken in connection with the accompanying drawings the construction and advantages of my improved form of mounting should be apparent and it will be seen that I have provided a novel and improved structure of combination mounting in which the metallic and non-metallic parts of the frame are split adjacent the bridge and satisfactorily united 30 one with the other, and in which the pivot spring and other associated parts of the mounting for the retaining lever are associated in a neat, compact and inconspicuous manner satisfactorily protected from dirt 35 or the like, and which, therefore, provides an extremely attractive appearing mounting, which will maintain its appearance under roughest service conditions and at the same time give maximum amount of wear.

45 I claim:

1. In an eyeglass mounting the combination of a split lens enclosing ring, a nose bridge attached to one of its ends, a sleeve attached to the other end of said ring, a 50 resilient fingerpiece mechanism carrying a nose grip and pivotally mounted on the bridge section of the rim and projecting

within said sleeve, and means for fastening the ends of said ring together.

2. In an eyeglass mounting the combination of a split lens enclosing ring, a nose bridge attached to one of its ends, a sleeve attached to the other end of said ring, a resilient fingerpiece mechanism carrying a nose grip, a pivot stud mounted on the bridge and affording pivotal connection for 55 said fingerpiece mechanism, and a fastening member connecting said sleeve and pivot stud.

3. In an eyeglass mounting the combination of a split outer lens enclosing ring, an inner split lens holding ring, a nose bridge attached to one end of the inner ring, a sleeve attached to the other end thereof, a resilient fingerpiece mechanism pivotally mounted on 60 the bridge and projecting within said sleeve, and means for fastening the ends of said rings together.

4. In an eyeglass mounting the combination of a split outer lens enclosing ring, an inner split lens holding ring having a nose bridge secured to one end and a sleeve secured to the other end, a resilient fingerpiece mechanism pivotally mounted in said sleeve, a pivot stud mounted on the bridge and affording pivotal connection for the finger piece mechanism and a screw intersecting the sleeve and pivot, substantially as 65 and for the purpose described.

5. A combination frame including a split metallic frame member, a bridge secured to one end of said frame member, a sleeve carried by the other end of said frame member, a non-metallic frame member extending around the metallic frame member, means for uniting one end of the non-metallic frame member with the bridge and the opposite end with the sleeve, means for securing the sleeve and bridge together to 70 unite the parts, and a fingerpiece actuating mechanism pivoted to the bridge and contained and concealed within the sleeve.

In testimony whereof I have affixed my signature, in presence of two witnesses.

C. O. COZZENS.
